UNITED STATES PATENT OFFICE

161,326

COMBINATION BATHROOM UNIT

Randolph Evans, Bronxville, N. Y.

Application July 3, 1950, Serial No. 10,955

Term of patent 14 years

(Cl. D4—4)

To all whom it may concern:

Be it known that I, Randolph Evans, a citizen of the United States of America, and a resident of Bronxville, New York, have invented a new, original, and ornamental Design for a Combination Bathroom Unit, of which the following is a specification, reference being had to the accompanying drawing, forming a part thereof, in which:

Fig. 1 is a front perspective of the combination bathroom unit with its swinging partition shown in closed position.

Fig. 2 is a front perspective of the combination bathroom unit with its swinging partition shown in partly open position.

Fig. 3 is a front perspective of the combination bathroom unit with its swinging partition shown in fully open position to expose the wash basin.

Fig. 4 is a corner perspective, viewing the combination bathroom unit from the left.

Fig. 5 is a corner perspective, viewing the combination bathroom unit from the right.

Fig. 6 is a top view of said combination bathroom unit.

Fig. 7 is a top view with the ceiling broken away to expose the inside of the combination bathroom unit, and showing the swinging partition in closed position as in Fig. 1.

Fig. 8 is a top view with the ceiling broken away to expose the inside of the combination bathroom unit, and showing the swinging partition in partly open position as in Fig. 2.

Fig. 9 is a top view with the ceiling broken away to expose the inside of the combination bathroom unit, and showing the swinging partition in fully open position as in Fig. 3.

Fig. 10 is a left side view of the combination bathroom unit with its left wall partly broken away to expose the toilet compartment.

I claim:

The ornamental design for a combination bathroom unit, as shown and described.

RANDOLPH EVANS.
